UNITED STATES PATENT OFFICE.

EDWARD F. KAPUS, OF ST. JOSEPH, MISSOURI.

TOY WAGON.

SPECIFICATION forming part of Letters Patent No. 724,296, dated March 31, 1903.

Application filed December 9, 1902. Serial No. 134,483. (No model.)

To all whom it may concern:

Be it known that I, EDWARD F. KAPUS, a citizen of the United States, and a resident of St. Joseph, in the county of Buchanan and State of Missouri, have made a certain new and useful Invention in Toy Wagons; and I declare the following to be a full, clear, and exact description of the same, such as will enable others skilled in the art to which it applies to make and use the invention, reference being had to the accompanying drawings, and to letters and figures of reference marked thereon, which form a part of this specification.

Figure 1 is a perspective view of my invention as applied. Fig. 2 is a transverse section of the same forward of the lever 5 and looking toward the rear. Fig. 3 is a fragmentary longitudinal section of the rear end of the wagon with the seat turned over. Fig. 4 illustrates a modified form of crank-plate. Fig. 5 is a plan view of the crank-plate and connecting-rod 8 in detail. Fig. 6 is a detail perspective view of a modified form of the invention.

The invention relates chiefly to propelling attachments for children's wagons; and it consists in the novel construction and combinations of parts, as hereinafter set forth.

In the accompanying drawings, illustrating the invention, the letter *a* designates the body of a toy wagon, and *b b* the wheels thereof.

c represents the hand-power attachment, which is designed to be easily and quickly attached to and detached from an ordinary vehicle, especially a child's wagon, while being neat in appearance, of light weight, substantial, durable, and economical in its manufacture. In connection therewith is provided an adjustable seat *d* and a guiding attachment *e*.

To the body *a* of the wagon is attached a transverse fulcrum-rod 2 by suitable hangers 3 and bolts 4, and upon the extremity of the rod 2 is pivoted a lever 5, being secured in position therein by means of a sleeve-collar 6 and its set-screw 7. The end of the rod 2 projects laterally from the body of the wagon sufficiently to provide for clearance of the wheel *b* by the connecting-rod 8, which extends from the lower arm of said lever to

the adjustable crank-plate or wheel-crank attachment 9. The extension *f* of the rod 2 is also designed to provide two journal portions separated from each other by the collar 5 for the reception of the two bearings of the lever, whereby stability of position for the handle-arm, as well as steadiness of working, is attained. The wheel-crank attachment is made in the form of a plate, which is placed upon the hub portion of the wheel and is secured to the wheel by means of the crimps 10 or inward projections of its marginal portion engaging the spokes 11. The connecting-rod is made with inward-bent 65 ends, which engage perforations in the end of the lower arm of the lever and in the crank projection of the crank-plate. This construction may be modified by using pivots, if desirable; but it is not so economical or 70 strong.

The lever 5 is provided with a handle portion 12 of suitable form for easy manual operations in effecting rotation of the wheel.

The wagon is guided by means of the tongue, 75 to which is attached a detachable and adjustable guide-bar 17.

A holding-hook 15 to prevent the tongue from falling forward is usually provided with the attachment, such hook being readily attached to and detached from the tongue and having its downward-turned end or ends engaging the front of the wagon.

The seat 16 is raised in position when the handle attachment is used and is detachable, 85 being connected to the body by means of hinge devices or link-plates 19, which may be removed. It consists of a box-like body having a hinged bottom 20, which when the seat-box is turned back against the end of the wagon-body becomes a cover to the box attachment. When the attachment is turned up, it rests on the side walls of the wagon and becomes a seat. Its depth, including its side arms 18, is equal to the depth of the side wall of the 90 wagon.

The hand-power attachment may be duplicated, levers, crank-plates, and connecting-rods being provided on each side for operation in connection with each of the rear wheels. 100

Instead of connecting the wheel-crank attachment to the spokes of the wheel it may

be connected to the hub of the wheel; but the spoke connection is preferred, having more spread or purchase.

I am aware that the construction can be varied by those skilled in the art without departing from my invention, and therefore I do not wish to be confined to the exact construction shown and described.

What I claim, and desire to secure by Letters Patent, is—

1. For a child's wagon, the detachable propelling attachment comprising the transverse fulcrum-rod, its means of attachment, the lever pivoted thereon, the detachable wheel-crank attachment, and the connecting-rod from said lever to said wheel-crank attachment, substantially as specified.

2. For a child's wagon, the detachable propelling attachment comprising the transverse

fulcrum-rod, its means of attachment, the double-bearing lever thereon, the sleeve-collar and set-screw, the wheel-crank plate, its means of attachment, and the connecting-rod, substantially as specified.

3. For a child's wagon, the detachable propelling attachment comprising the transverse fulcrum-rod, its means of attachment, the double-bearing lever thereon, the sleeve-collar and set-screw, the marginally-crimped wheel, crank-plate, and the connecting-rod, substantially as specified.

In testimony whereof I affix my signature in presence of two witnesses.

EDWARD F. KAPUS.
